C. S. WEEKS

ART OF WRAPPING PACKAGES

Filed Dec. 21, 1920

UNITED STATES PATENT OFFICE.

CHARLES S. WEEKS, OF SOUTH ORANGE, NEW JERSEY, ASSIGNOR TO WEEKS ENGINEERING CORPORATION, OF NEW YORK, N. Y., A CORPORATION OF NEW YORK.

ART OF WRAPPING PACKAGES.

Application filed December 21, 1920. Serial No. 432,168.

To all whom it may concern:

Be it known that I, CHARLES S. WEEKS, a citizen of the United States, residing at South Orange, county of Essex, and State of New Jersey, have invented certain new and useful Improvements in the Art of Wrapping Packages, of which the following is a specification.

This invention pertains to the art of enclosing an article within a wrapper, and it is directed, more specifically, to an improvement in the mode of enclosing a bottle or other container, with or without an accompanying circular or other insert, by the direct application thereto of a wrapper composed of paper or other pliable material, whereby the cost of a stiff carton and the attendant labor of enclosing the package within such carton may be avoided, thus attaining economy of time and labor in wrapping a package, and attaining, also, a form which lends individuality to said package and is acceptable to the trade.

In this art it is desirable, among other things, to apply the wrapper in such manner that the end fold, at one or both ends of the package, simulates the appearance of a label separately applied to said end; further, to so distribute the material of the end fold as to appreciably stiffen or stay the corners of the package at the end thereof, thereby precluding to a substantial extent that tendency of a non-reinforced wrapper to break down or collapse at the corners when packing the wrapped packages for shipment or storage or when handling the same; and, further, to so position the plies or folds of the material composing said end fold as to attain smooth surfaces for the required contact of said surfaces in the act of sealing said end fold.

With these ends in view, the invention, in one aspect thereof, is embodied in an end closure formed by folding the wrapper in a desired manner, a characteristic feature being the provision of printed matter on the parts or folds of said end closures whereby the effect is gained of an end label, portions of which extend to the side or sides of the wrapper so as to simulate the ap-

pearance of a label applied separately to the package.

The end closure is constituted by a desired folding of the material composing the wrapper, one or both ends of which protrude in tubular form beyond the corresponding end or ends of the package. Said end closure embodies a plurality of folds one or more of which in the manipulation of the material extend outwardly with respect to a side or sides of the package, said outwardly extending fold or folds being turned parallel to the side or sides of the wrapper and preferably affixed thereto, and the exposed end fold and, preferably, the side fold or folds, being provided with the aforesaid printed matter in simulation of the label.

The preferred mode of procedure which constitutes the method in its entirety of enclosing an article within a wrapper according to this invention includes the following operations, which may be performed manually or mechanically:—Positioning the article or container, with or without a circular or other insert, within a wrapper at least one end of which is tubular, which tubular end protrudes beyond the corresponding end of the article or container; folding a side portion of said tubular protruding wrapper end inwardly with respect to said article or container, thereby producing an inwardly folded flap, which is thus interiorly positioned in the completed end closure, and leaving in an unfolded condition a second side flap, hereafter termed a sealing flap, and two corner flaps; next folding one or both corner flaps in outward directions with respect to the infolded flap, such outward folding of one or both flaps causing the same to project beyond the limit of the package at one or both sides thereof, and concurrently with said outward folding of one or both corner flaps the sealing flap is folded inwardly with respect to the first mentioned side flap, the latter having been initially turned inward as described; then bending one or both corner flaps around the corners of the package at the end thereof, such bending of the corner flap or flaps serving to

position the same into lapping contact with the sides of the package on the exterior surface thereof, and affixing the sealing flap and one or both corner flaps in fixed relation to the wrapper.

Other features and advantages of the invention will appear from the following description taken in connection with the drawings, wherein:—

10 Figure 1 is a perspective view illustrating a wrapper in an early stage of its application to an article or a container of one kind or another.

Figure 2 is a perspective view showing the 15 inward folding of a part of the protruding tubular end of the wrapper.

Figure 3 is a perspective view with the 20 end portion of the wrapper folded to produce the laterally-extending corner flaps and 25 the sealing flap, the said flaps being partially folded toward the final stages and illustrating the label effect desired to be obtained.

Figure 4 is a perspective view with the 25 sealing flap in the final position, but with 30 the two corner flaps in extended relation to the respective sides of the wrapper.

Figure 5 is a perspective view of a 35 wrapped package, illustrating the effect of a label separately applied to the package by 40 an apparent extension of the ends of said label around the corners of the package.

Figure 6 is a detail cross section through 45 a corner of the folded wrapper showing the mode of folding the material with a view to 50 increasing the stiffness of the wrapper at the respective corners thereof.

The wrapper A is initially a flat sheet of 55 rectangular material, such as paper, the same having any desired matter printed 60 thereon, which matter includes a simulated label, indicated at b, printed upon that portion of the wrapper which in this invention constitutes the end closure of the package. Of course, the printed matter on the wrapper 65 is wholly immaterial, but to enhance the label effect at the closed end of the package it is desirable in some instances to print the label subject matter, including the ornamentation, on the wrapper.

50 The wrapper A is folded around the container, or other desired article generally rectangular in form and with flat sides, in a manner for the tubular end of the wrapper to protrude at c in Figure 1 for an appreciable and definite distance beyond the corresponding end of the article or container, the side edges of the wrapper being overlapped and sealed to produce a lap or seam d extending lengthwise of the wrapper and 60 located at any desired point between the opposite sides or at a corner of the resulting package, see Figure 1.

At the protruding tubular end of the 65 wrapper, one side portion at the lap or seam d is now pressed inwardly across the

hitherto open tubular end of said wrapper, producing a side flap e, the form and dimensions of which are such as to close, partially or wholly, said open end, see Figure 2.

The infolding of said flap e leaves the 70 other side f and the corners g h in protruding relation to said flap e, see Figure 2, but the first infolding operation doubles the material at the two corner portions g, h, 75 each corner portion g or h being formed in part by an extension of that portion of the wrapper lying in the plane of one narrow side of the package and in part by the infolded material; in other words, each portion g h consists of two plies in lapping relation, the free edge of one of said plies being substantially in contact with the sealing flap f, see Figure 2.

Prior to the described first folding operation, or it may be subsequently thereto, spots i, j, of paste or other adhesive are applied to flap f as indicated in Figure 2, and other spots k of adhesive are applied to the wrapper at the narrow sides of the package. When the material of the 90 tubular protruding end is infolded as in Figure 2, the doubled over plies of material at the respective corners g h are sealed by the spots i of adhesive, the latter being 95 partially concealed by the doubled over material, whereby the two plies of material at each corner g or h are adhesively secured.

The double thickness of material at the corners g h and the sealing flap f are now 100 folded as shown in Figure 3. The doubled material at each corner g, h, is folded on the line l in Figure 2, resulting in corner flaps g' h', one at each side, said corner flaps g' h', extending outwardly with respect to 105 the infolded flap e and the sealing flap f; in other words, said corner flaps g' h' are not infolded to lie between the two said flaps e, f, as has been the practice hitherto.

The outward folding of the material to 110 produce the laterally extending corner flaps g' h' draws upon the sealing flap f as shown in Figure 3 so as to position it toward contact with the infold e, the uncovered spots of adhesive i j affixing the flap f to and 115 against the flap e, as shown in Figure 4, suitable pressure being applied to effect the sealing operation.

The sealing flap f is of such form and 120 dimensions that it substantially covers the area of the end of the package, the two flaps e f when sealed together constituting the 125 end closure for the wrapper.

At this stage, the folded flaps g' h' occupy 130 positions in laterally extended relation to and beyond the narrow sides of the package, at the end thereof, see Figure 4, the printing b in imitation of the label appearing in full upon the sealing flap f and the two corner flaps g' h'. The operation of sealing the wrapper is completed by bend-

ing the flaps $g' h'$ around the corners of the package, and affixing said corner flaps by the spots k of adhesive to the respective sides of the package, pressure being suitably applied to effect the bending of the doubled material composing the corner flaps and to seal said doubled corner flaps $g' h'$ to the wrapper at the narrow sides of the resulting package.

10 Several important functions are attained by first folding the doubled material constituting the corner flaps $g' h'$ so as to extend said corner flaps outwardly beyond the narrow sides of the package, and thereafter bending said corner flaps $g' h'$ into substantially parallel relation to the narrow sides of said package.

Such operation doubles the cross sectional thickness of the material at each corner as 20 shown in Figure 6, the effect of which is to materially stiffen the corner, the additional material acting as a stay, whereby the corners are reinforced to a substantial extent with a view to precluding the corners from crushing down or collapsing, an advantage especially desirable in a package the interior of which is free from the stiffening afforded by a carton or a paste board lining. Again, the end closure is free from folded 25 material interposed between the end flap e and sealing flap f , the surfaces of which remain in a smooth condition for the spread of the adhesive and for the application of the pressure required to affix the sealing flap to the end flap. Furthermore, the wrapper is or can be printed on that portion which 30 constitutes the sealing flap to present the appearance of a label upon the end closure of the package, the sealing flap having a continuous surface undivided by seam d . By extending the label printing to the portions of the wrapper forming the exteriorly folded corner flaps $g' h'$, the label effect is 35 increased to a marked extent for the reason that the sealing flap f and the corner flaps $g' h'$ form a continuous surface substantially covering the end and extending around the corners and onto opposite sides of the package. Hence such an end closure 40 presents to the eye the appearance of a label separately applied and pasted around the corners of the package.

Having thus fully described the invention, 45 what I claim as new and desire to secure by Letters Patent, is:

1. A package wrapper of tubular form having an undivided external end closure integral therewith and covering substantially the entire end of the package, said end closure having reinforcing flaps of plural thickness extending therefrom and folded toward the adjacent exterior sides of the package.

2. A package wrapper of sheet material 50 and of tubular form, having an undivided

external end closure covering substantially the entire end of the package, with a reinforcing flap of multiple layers extending therefrom, the outermost layer being an extension of the sheet material of said undivided end closure.

3. A package wrapper having a body portion of tubular form and an undivided external end closure bearing the simulacrum of a label, said end closure having reinforcing flaps of multiple thickness integral with the body and with the end closure of the wrapper, said flaps being folded toward the exterior sides of the package adjacent said end closure.

4. A package wrapper of tubular form, having integral therewith an undivided external end closure covering substantially the entire end of the package and bearing the imprint of a label, with a reinforcing flap of more than one thickness extending from said end closure and secured to an exterior side of the package.

5. The method of wrapping a package of substantially rectangular form which comprises, folding sheet material into a substantially rectangular polyhedron, substantially covering the end of the package by folding a portion of an undivided side of the material over the end of the package so as to form an undivided surface, folding portions of those opposite sides which are adjacent the side first folded to extend outwardly as reinforcing flaps, and folding said reinforcing flaps toward the sides of the package.

6. The method of wrapping a package of substantially rectangular form which comprises, folding a rectangular sheet of material having continuous edges into a substantially rectangular polyhedron, substantially closing the end opening with an appropriate portion of a side thereof, covering said end-closing portion with a similar portion of an undivided side to form an undivided surface over substantially the entire end of the package, and folding the flaps thus formed toward the sides of the package.

7. The method of wrapping a package of rectangular form which comprises, folding sheet material into a rectangular polyhedron, substantially closing the end opening with an appropriate portion of a side thereof, folding inwardly portions of the sides of the wrapped material adjacent thereto along a line running diagonally across said portions, substantially covering the folded portion of the first mentioned side with a portion of the opposite side, and smoothing out the diagonally folded portions as extending flaps and securing said flaps to sides of the package.

8. The method of wrapping a package which comprises, partially enclosing an article with sheet material bearing the simulacrum of a label on an undivided portion

thereof, forming a tubular end extension of said label portion and folding said label portion to form an undivided exterior end closure and reinforcing flaps extending therefrom adapted to be secured to sides of the package.

9. The method of wrapping a package which comprises, partially enclosing an article with sheet material bearing the simula-

crum of a label on an undivided portion 10 thereof, forming a tubular end extension of said label portion, and folding said label extension to give a continuous surface substantially covering the end and extending on to opposite sides of the package. 15

In testimony whereof I have hereto signed my name this 17th day of December, 1920.

CHARLES S. WEEKS.

thereof, forming a tubular end extension of said label portion and folding said label portion to form an undivided exterior end closure and reinforcing flaps extending therefrom adapted to be secured to sides of the package.

9. The method of wrapping a package which comprises, partially enclosing an article with sheet material bearing the simula-

crum of a label on an undivided portion 10 thereof, forming a tubular end extension of said label portion, and folding said label extension to give a continuous surface substantially covering the end and extending on to opposite sides of the package. 15

In testimony whereof I have hereto signed my name this 17th day of December, 1920.

CHARLES S. WEEKS.

Certificate of Correction.

It is hereby certified that in Letters Patent No. 1,556,056, granted October 6, 1925, upon the application of Charles S. Weeks, of South Orange, New Jersey, for an improvement in "The Art of Wrapping Packages," an error appears in the printed specification requiring correction as follows: Page 3, after line 52 insert the paragraph—

Although I have shown and described the two corner flaps as standing outwardly and sealed to the respective sides of the package, it will be understood that I reserve the right to infold the material of one corner flap and extend outwardly the material of the other corner flap.;
and that the said Letters Patent should be read with this correction therein that the same may conform to the record of the case in the Patent Office.

Signed and sealed this 15th day of December, A. D. 1925.
